UNITED STATES PATENT OFFICE.

LOUIS FRANK, OF BROOKLYN, AND JOSEPH COOPER, OF NEW YORK, N. Y., ASSIGNEES
TO GREENPOINT METALLIC BED COMPANY, OF BROOKLYN, NEW YORK, COMPOSED
OF DAVID FRANK, OF BROOKLYN, NEW YORK, JOHN TROUNSTINE, OF NEW YORK,
N. Y., AND WILLIAM LIES, OF BROOKLYN, NEW YORK.

METALLIC BEDSTEAD.

1,210,924.

Specification of Letters Patent. Patented Jan. 2, 1917.

Application filed March 1, 1915. Serial No. 11,183.

To all whom it may concern:

Be it known that we, LOUIS FRANK, a subject of the Czar of Russia, and a resident of Brooklyn, in the county of Kings and State of New York, (whose post-office address is 159 Milton street, Brooklyn, New York,) and JOSEPH COOPER, a subject of the Czar of Russia, residing in New York city, in the county and State of New York, (whose post-office address is 406 East Twentieth street, New York city, New York,) have invented certain new and useful Improvements in Metallic Bedsteads, of which the following is a specification.

The invention pertains more particularly to metal bedsteads whose head and foot frames are of ornamental character and composed mainly of tubing, the tubing sometimes being rectangular in cross-section and at other times of other shape in cross-section.

The object of the present invention is to provide means for further ornamenting and varying the style of the head and foot frames of tubular metal bedsteads, and more particularly to provide constructions of head and foot frames having cane panels therein, these panels serving to render said frames ornate and to permit those modifications in head and foot frames serving to render the bedsteads quite different in design from one another and of attractive character.

The invention will be fully understood from the detailed description hereinafter presented, reference being had to the accompanying drawings, in which:

Figure 1 is a perspective view of an end frame for a metal bedstead equipped with the cane-panel features constituting our invention; Fig. 2 is an enlarged view of a portion of the same and showing more particularly those portions of said frame which receive and hold the cane-panel; Fig. 3 is a horizontal section, partly broken away and on a larger scale, through the central portions of the end frame shown in Fig. 1; Fig. 4 is an enlarged horizontal section through a portion of the end frame, this section being taken about on the dotted line 4-4 of Fig. 5 and Fig. 4 illustrating a somewhat different form of frame to receive the edges of the cane panel from the frame an-

swering the same purpose shown in Fig. 3, and Fig. 5 is a detached face view, on a smaller scale, of a portion of the end frame represented in Fig. 4, Fig. 5 showing what may be termed the inner face of the end frame.

In the drawings, 10 designates an end frame for a metal bedstead, said frame comprising corner posts 11, upper and lower transverse tubular members 12 connecting said corner posts and vertical rods or members 13, 14 extending between and connecting said horizontal members 12. The vertical members 13, 14 vary in character and disposition, but are of ordinary construction, and in the present instance the vertical members 14 are sufficiently separated from each other to create an outline as well as support for the panel 15 formed of cane in sheet form, the sheet being made from strips woven together according to well-known methods.

The vertical tubular members 14 have secured upon their facing sides metallic channel strips or frame sections 16 and upon the facing sides of the horizontal members 12 are secured corresponding metallic channel strips or frame sections 17 (Fig. 2), the strips 16, 17 forming a continuous grooved frame secured to the adjacent members of the bedstead frame and being preferably formed from sheet metal and secured in position by solder. The cane-panel 15 has its edges secured within the grooves of the channel frame sections 16, 17 and stretches over the entire outline defined by said sections.

Ordinarily the edges of the cane-panel 15 are folded over and entered within the grooves afforded by the frame sections 16, 17 and there secured by driving a reed or wire rod or the like 18 down into such grooves and between the folded-over portions at the edges of the panel 15. After the reed or rod 18 has been introduced to the position shown in Fig. 3 binding the cane-panel 15 in position, the inner sides of the frames 16, 17 may be forced outwardly to a slight extent to pinch said reed or rod and thus aid in firmly securing the panel in position.

The metallic frame sections 16, 17 will vary in dimensions in accordance with the

position they are to occupy and the general effect sought to be created by the cane-panel 15, and in Figs. 1, 2 and 3 we illustrate such sections as being composed of a short side 19 5 to be soldered to the adjacent metal surface of the bed and a longer side 20 over which the cane extends.

In the construction shown in Figs. 1, 2 10 and 3 the cane-panel 15 is, by reason of the longer sides 20 of the frame sections 16, 17 set inwardly to some considerable extent from the outer vertical plane of the bedstead frame. The effect may be varied by modifying the depth of the sides 20, so that the cane-panel 15 may be given just the desired 15 location with relation to the outer and inner vertical planes of the bedstead end frame.

In the construction shown in Figs. 4 and 5 20 the metallic channel-frame numbered there- 20 in as 21 is more shallow than the channel frame made of the sections 16, 17 hereinbefore referred to, and hence the setting inwardly of the cane-panel is less pronounced 25 with the use of the shallow channel frame 21 than when the sections 16, 17 are made use of. The edges of the cane-panel, numbered 22 in Figs. 4 and 5, these figures showing a modification, are forced into the 30 grooves of the frame 21 and there held by means of reeds or wire rods 23 which in addition to being pinched between the sides of the frame 21 are additionally secured by means of small metallic strips 24 which are secured at one end to the members of the 35 bedstead frame and capable of being bent over upon the reeds or rods 23. There may be as many of the strips 24 employed as desired, but usually only a few of such strips will be necessary.

40 Our invention presents a novel style of end frame for metal bedsteads in that said frame embraces a woven cane-panel with suitable means for securing the same in position. We have illustrated the panel as extending the full height of the end frame, but 45 do not limit our invention to this arrange-

ment, because the panels will vary in shape with the style of the end frame and some of the panels will be extended horizontally for some end frames and others vertically 50 and it will not be necessary at any time to so construct the end frame of the bedstead that the panel must necessarily extend the full height of such end frame. We have therefore illustrated one general embodiment 55 of the invention without meaning thereby to limit the application of our invention to bedstead end frames of any special character other than the application of our invention thereto may require. 60

What we claim as our invention and desire to secure by Letters-Patent, is:

1. An end-frame for a metal bedstead comprising metal corner posts, transverse members connecting the same, vertical members connecting said transverse members and a woven cane panel interposed in said end frame and secured at its edges to portions of members thereof, said portions having affixed thereto channel sections for receiving folded-over edges of said panel and strips for wedging said edges in said sections, and metal strips being provided to be bent over on said wedge strips for securing the same in said channel sections. 75

2. An end-frame for a metal bedstead comprising metal corner posts, transverse members connecting the same, vertical members connecting said transverse members and a woven cane panel interposed in said end 80 frame and secured at its edges to portions of members thereof, said portions having affixed thereto channel sections for receiving folded-over edges of said panel and strips for wedging said edges in said sections, means being provided for securing said strips in said channel sections. 85
